(57) **CLAIM**

The ornamental design for a display screen or portion thereof with graphical user interface, as shown and described.

DESCRIPTION

The FIGURE is a front view of a mobile phone having a display screen with a graphical user interface showing our new design.

The notched vertically-oriented round-cornered rectangular broken line border shows the perimeter of a display screen. The broken lines outside this border show portions of a mobile phone. The broken lines within the border depict portions of a graphical user interface. The broken lines form no part of the claimed design.
